UNITED STATES PATENT OFFICE.

DANIEL ZATZKE, OF MUSKEGON, MICHIGAN.

MOLD.

1,282,161.

Specification of Letters Patent.

Patented Oct. 22, 1918.

Application filed August 15, 1918. Serial No. 249,974.

To all whom it may concern:

Be it known that I, DANIEL ZATZKE, a citizen of the United States, residing at Muskegon, in the county of Muskegon and State 5 of Michigan, have invented certain new and useful Improvements in Molds, of which the following is a specification.

The mold which is the subject matter of the present application for patent is designed 10 for molding building blocks of concrete or analogous material, and more particularly blocks of this kind which are formed with an opening to provide an air space in the wall constructed of such blocks.

15 The invention has for its object to provide a simple and efficient mold for blocks of the kind stated, together with novel and improved means for forming the opening in the block.

20 The object stated is attained by means of a combination and arrangement of parts to be hereinafter described and claimed, and in order that the same may be better understood, reference is had to the accompanying 25 drawings, forming a part of this specification.

In the drawings,

Figure 1 is an elevation of the mold;

Fig. 2 is an end view thereof;

30 Fig. 3 is a cross section;

Fig. 4 is a longitudinal section on the line

4—4 of Fig. 2;

Fig. 5 is a view similar to Fig. 4 showing a core inserted into the mold;

35 Fig. 6 is a perspective view of the block which the mold is designed to form, and

Fig. 7 is a central longitudinal section of said block.

Referring specifically to the drawing, the 40 block to be molded is shown at 5, the same being rectangular in contour and having a longitudinal horizontal opening 6 extending from one end of the block to the other. The ends of the block, above the opening, have recesses 7 to facilitate handling. Figs. 6 and 45 7 clearly illustrate the block.

The mold for the hereinbefore described block is a box having sides 8, a bottom 9 and a top 10. The sides and bottom are rigidly 50 connected in any suitable manner, and the top is separate so that it may be removed, it being put in place after the mold is filled and pressed down by suitable means to compress the concrete or other material in the mold to a certain extent, after which a core block is forced through to complete the

tamping. The bottom 9 and the top 10 carry core blocks 11 for forming the recesses 7.

The mold box is also provided with end walls 12 having vertical hinge connections 13 60 with one of the side walls 8, and secured to the opposite side wall by a suitable latch 14.

Each end wall 12 supports a pair of sliding doors 15 positioned one above the other, the wall having guides 16 in which the vertical edges of the doors seat. These doors separate vertically to open, and they are of the same width as that of the opening 6 in the block 5. The doors are held normally closed by contracting coil springs 17, and 70 when closed the inner edges of the doors are slightly spaced, these edges carrying horizontally positioned rollers 18 to facilitate the insertion of a core bar 19 by which the opening 6 is formed. 75

The core bar 19 is advanced horizontally between the rollers 18 at one end of the mold, and upon continuing its advance, the doors 15 separate to allow the bar to be passed through the mold. The entrance end of the 80 core bar is pointed and when the stroke is finished the pointed end of the bar has entered between the rollers at the farther end of the mold, thereby spreading the doors at this end, after which the core bar is withdrawn to the end it entered. The core bar is 85 operated by any suitable power means and as it is forced through the material in the mold, it forms the opening 6. The nature of the material under pressure is such that it 90 remains compressed, so that when the core bar is withdrawn, the opening 6 will remain and not diminish in size. The core bar being pointed, it compresses the material as it is forced through the same, and the sliding doors prevent the material from being pushed out, the springs keeping them close 95 to the core bar.

It will be understood, of course, that the 100 end walls 12 have openings 20 to accommodate the core bar 19, and after the block 5 is finished these walls are swung open and the top 10 is taken off for removal of the block from the mold.

I claim:

1. In a block mold, a bottom, side walls, movable end walls having openings, slidable doors over said openings, and a core bar inserrible into the mold between the doors and through the openings. 105

2. In a block mold, a bottom, side walls, movable end walls having openings, slidable

- doors over said openings, and a core bar insertible into the mold between the doors and through the openings, said core bar having a pointed entering end to force the doors open.
5. 3. In a block mold, a bottom, side walls, movable end walls having openings, oppositely slidable doors over said openings, and a core bar insertible into the mold between the doors and through the openings.
10. 4. In a block mold, a bottom, side walls, movable end walls having openings, oppositely slidable doors over said openings, and a core bar insertible into the mold between the doors and through the openings; said core bar having a pointed entering end to force the doors apart.
15. 5. In a block mold, a bottom, side walls, hinged end walls having openings, slidable doors over said openings, and a core bar insertible into the mold between the doors and through the openings.
20. 6. In a block mold, a bottom, side walls, movable end walls having openings, a slideable closure for the openings, and a core bar insertible into the mold past the closure and through the openings.
25. 7. In a block mold, a bottom, side walls,

movable end walls having openings, a slideable closure for the openings, and a core bar 30 insertible into the mold through the openings and engageable with the closures for opening the same.

8. In a block mold, a bottom, side walls, movable end walls having openings, oppositely 35 slidable closures for the openings, and a core bar insertible into the mold through the openings, and between the closures for forcing the same apart.

9. In a block mold, a bottom, side walls, 40 movable end walls having openings, oppositely slidable closures for the openings, rollers mounted at the adjacent ends of the closures, and a core bar insertible into the mold through the openings, and between the rollers 45 for forcing the closures apart.

10. In a block mold, a bottom, side walls, movable end walls having openings, a slideable closure for the openings, a core bar insertible into the mold past the closure and 50 through the openings, and springs engageable with the closures for holding the ends thereof in contact with the core bar.

In testimony whereof I affix my signature.

DANIEL ZATZKE.
